MIXING EQUIPMENT

Richard D. Boutros, Brighton, N. Y., assignor to
Mixing Equipment Co., Inc., Rochester, N. Y.,
a corporation of New York

Application September 16, 1950, Serial No. 185,277

8 Claims. (Cl. 286—9)

1

This invention relates to material agitating and mixing means and more particularly to the variety thereof in which the materials are mixed in a tank or other receptacle having a motor driven shaft extending through a wall of the tank and provided therein with a propeller or other agitating means, one object of the invention being to provide an improved apparatus of the above character having a more simple, practical and convenient construction.

In such an apparatus, the opening in the tank wall through which the shaft extends requires sealing by suitable packing means such as the known stuffing box the packing material of which requires replacement from time to time and a further object of the invention is to provide an improved auxiliary means for temporarily sealing the tank opening while such packing material is being replaced, without having to first lower the contents of the tank below the level of the stuffing box.

Another object of the invention is to provide a mixing device having an improved bearing structure for supporting the shaft and by means of which the shaft can be easily moved a short distance longitudinally to operate the above auxiliary sealing means.

A further object of the invention is to provide a mixing device of the above character with means for supplying the auxiliary sealing means with a flushing fluid under pressure to prevent the contents of the receptacle, often of a corrosive nature, from contacting the auxiliary sealing means and the packing in the stuffing box.

Still a further object of the invention is to provide a mixing device that is adapted for use either as a side or top entering mixer and which, with a minimum of transposition of parts, may also be used as a bottom entering mixing device.

To these and other ends the invention resides in certain improvements and combinations of parts, all as will be hereinafter more fully described, the novel features being pointed out in the claims at the end of the specification.

In the drawings:

Fig. 1 is a side elevation of a mixing device embodying the present invention and shown as applied to a side of a mixing receptacle;

Fig. 2 is an enlarged elevation of the outer end of the above device as viewed from line 2—2 of Fig. 1;

Fig. 3 is an enlarged fragmentary top plan view, partly broken away and partly in section, substantially along line 3—3 of Fig. 1, showing the auxiliary sealing means and shaft supporting bearings;

Fig. 4 is an enlarged sectional plan view of the inner end of the mixing device as shown in Fig. 3;

Fig. 5 is an enlarged sectional plan view of the outer end of the mixing device showing the outer bearing construction;

Fig. 6 is an elevation of a slightly modified con-

2

struction, adapted for application to the bottom of a mixing receptacle;

Fig. 7 is an elevation of the construction shown in Fig. 6, partly in section and partly broken away, showing details of the construction, and

Fig. 8 is an enlarged sectional elevation of the upper portion of the mixing device as shown in Fig. 7, with the auxiliary sealing means in sealing position.

This invention is herein disclosed, by way of illustration, as embodied in a unit adapted for driving the impeller or agitator shaft of mixing equipment comprising a liquid container partly shown at 21 (Fig. 1), having side wall and bottom portions 23 and 25, respectively. In one adaptation of the invention, side wall 23 is formed with a nozzle 27 which has at the outer end thereof a flanged portion 29 to which the present device is adapted to be fastened. This adaptation preferably comprises an elongated frame shown generally at 31 (Fig. 3) having inner, middle and outer sections 33, 35 and 37, respectively, which are bolted together to form a rigid frame as shown. Frame 31 is secured at the inner end thereof by bolts 39 to a flange 41 which in turn is fastened to nozzle flange 29 by bolts 43. Frame 31 has adjacent the outer end and midportion thereof bearing structures shown generally at 45 and 47 (Fig. 3), respectively, for rotatably supporting an agitator drive shaft 49 which extends longitudinally through said frame, through nozzle 27 and into the container. Shaft 49 has a suitable agitating or impelling device, as, for example, a propeller, secured to the inner end thereof (not shown), as well understood in the art. A hollow quill 51 surrounding the midportion of shaft 49 is supported at the inner and outer ends thereof by quill bearings 53 and 55, respectively, and has its upper end connected to shaft 49 by a flexible coupling 57 of known and suitable construction. Frame 31 has a transversely projecting arm 59 for supporting an electric motor 61 which furnishes the power for operating the mixer. Motor shaft 63 is connected by coupling 65 to a worm (not shown) which in turn drives a worm gear (not shown) attached to quill 51. Reference is made to the patent to Hesse, No. 2,489,642, for a full and complete disclosure of the details of the above driving means.

A stuffing box shown generally at 67 (Figs. 3 and 4) having an inner end 69 (Fig. 4) and a cylindrical sleeve or body portion 71 is mounted on flange 41 so as to seal flanged container opening 27 to which the mixing device is secured. End 69 forms the outer end of a flushing chamber hereinafter more fully described, and extends into the container, contacting the materials therein. End 69 has an opening 73 bored therein, through which shaft 49 passes with minimum clearance therebetween. The inner diameter of sleeve portion 71 is substantially larger than the diameter of shaft 49, leaving a space 75 (Fig. 4) therebetween which is open at the outer end thereof and is adapted to receive a plurality of

packing rings 77 (Fig. 3) to prevent the contents of the container from escaping along shaft 49 through opening 73, as well understood in the art. Sleeve portion 71 has formed adjacent the open end thereof a transversely extending flange 79 (Fig. 3) which is adapted to be connected by bolts 81 and nuts 83 to a gland 85 for drawing said gland into space 75 to compress the packing rings and thereby insure a tight seal in said stuffing box.

Stuffing box 67 preferably comprises an extension thereof shown generally at 86 (Figs. 3 and 4) forming a flushing chamber which is connected to a supply of flushing fluid, as, for example, water, supplied under a pressure slightly greater than the pressure exerted by the contents of the receptacle, by means of which said receptacle contents are prevented from passing through opening 73 and contacting packing rings 77. This flushing chamber comprises a flushing cavity housing 87 (Fig. 4) attached to inner end 69 of stuffing box 67. The inner end 89 of housing 87 has formed therein an opening 91 through which shaft 49 passes with a minimum of clearance. To provide effective sealing at the inner end of the flushing chamber, shaft 49 is provided with a closely fitting flushing seal ring 93 of fiber, metal, or other suitable known material. A seal ring cap 95, secured to flushing cavity housing 87, is formed with a recess 96 which is adapted to receive seal ring 93 and securely position said ring against flushing cavity housing end 89 and shaft 49, as shown in Fig. 4.

Stuffing box sleeve portion 71 has formed therein an inlet 97 (Fig. 4) which is connected to opening 73 in end portion 69 by internal bores 98 and 101, as shown in Fig. 4, by means of which the flushing fluid passes into the flushing chamber. Although the flushing seal ring 93 and retaining cap 95 form an effective seal thereby reducing the interchange of the flushing fluid and contents of the receptacle, it should be noted that as the flushing fluid is under slightly greater pressure than that exerted by the contents of the receptacle, any leakage will be out of the flushing chamber into the receptacle and thus the receptacle contents will be prevented from contacting the packing rings. The flushing fluid is of such a character and in such small quantity as to avoid objectionable contamination of the contents of the container.

Shaft 49 is provided with an alternative sealing device which is adapted to temporarily engage the outer surface of inner end 69 of the stuffing box to seal opening 73 therethrough and prevent the contents of the receptacle from escaping along shaft 49 when it is desired to remove the packing from the stuffing box and the level of the contents in the receptacle is above the inner end of the stuffing box.

This temporarily sealing device comprises a closely fitting collar 103 (Fig. 4) secured to shaft 49 by a set screw 105 as shown in Fig. 4. Collar 103 is located inboard of end 69 of stuffing box 67, and when said stuffing box comprises a flushing chamber as described above, said collar is located within flushing cavity housing 87 as shown in Fig. 4. The opposite sides 107 and 109 of collar 103 have finished surfaces and when the shaft is moved outwardly through said stuffing box, by means to be hereafter described, side 107 of the collar closely engages outer surface 111 of stuffing box end 69 and forms therewith a tight seal to prevent the contents of the receptacle from passing through opening 73 into

the stuffing box when gland 85 is loosened and packing rings 77 are removed as shown in Fig. 4. To insure a more positive seal in instances where the tank contains toxic gases, and the like, a gasket 113 is positioned on shaft 49 between collar 103 and stuffing box end 69.

As stated earlier shaft 49 is rotatably supported on frame 31 by inner and outer bearing structures 47 and 45, respectively (Fig. 3), which are similar in construction so that a description of the inner bearing structure 47 will apply to both.

The inner or lower shaft bearing comprises preferably a recess or chamber 115 (Fig. 4) formed in the outer end 117 of inner frame section 33. Slidably fitted in chamber 115 is a ball bearing 119 of any known or suitable construction, having a tapered internal opening 121 engaging the correspondingly tapered outer surface portion 123 of a sleeve 125 fitted to the drive shaft 49. Sleeve 125 is of resilient metal split longitudinally and so capable of being contracted and releasably clamped to the shaft. For this purpose, one end of the sleeve has threadedly engaged therewith a thrust means or lock nut 127 carrying a washer 129 bearing against one end of sleeve 131 slidably longitudinally on a cylindrical portion of the outer surface of sleeve 125. The opposite end of sleeve 125 bears against ball bearing 119 for moving the same longitudinally to oppose the tapered surfaces 121 and 123 of the bearing and sleeve and so contract and clamp the split sleeve 125 on the shaft. A snap ring 133 is located adjacent the upper, open end of chamber 115 for limiting the longitudinal movement of the bearing. A dust seal 135, of any known or suitable construction, is located between chamber 115 and sleeve 131 as shown in Fig. 4.

The outer or upper shaft bearing, as seen in Fig. 3, and the means for moving the shaft longitudinally to actuate the above auxiliary sealing device comprises a bearing housing 141 (Fig. 5), having oppositely extending handles 143. Housing 141 threadedly engages a flange 145 located at the outer or free end of outer frame section 37. Threaded bearing housing 141 has formed therein a recessed chamber 147 (Fig. 5) similar to chamber 115. A ball bearing 149 similar to bearing 119 is held in position in chamber 147 by a snap ring 151. Bearing 149 has a tapered internal opening 153 engaging the tapered portion 155 of a split sleeve 157. Bearing 149 is held in engagement with tapered portion 155 of sleeve 157 by a lock nut 159 carrying a washer 161 bearing against one end of a sleeve 163. Said sleeve, lock nut and washer are identical with lower bearing lock nut 127, washer 129 and sleeve 131, respectively. The upper bearing structure has, in addition, snap rings 165 and 167 secured to shaft 49 adjacent the inner and outer ends of split sleeve 157 the purpose of which is to prevent relative movement between sleeve 157 and shaft 49. A dust seal 169 closes the inner end of recess chamber 147, the outer end of which is closed by a frictionally fitting cap 171.

It is evident from the above description of the outer bearing structure that when lock nut 159 is tightened on sleeve 157, as shown in Figs. 3 and 5, it draws sleeve 157 and shaft 49 downwardly until tapered portion 155 of sleeve 157 engages tapered portion 153 of bearing 149 which in turn is held in place in threaded outer bearing housing 141 by snap ring 151. Thus, bearing 149, sleeve 157 and shaft 49 are held one to

another and can be moved longitudinally as a single unit. Consequently, to move shaft 49 outwardly through frame 31 it is only necessary to loosen lower bearing lock nut 127 from its position as shown in Fig. 3 to its position as shown in Fig. 4, thereby allowing relative movement between shaft 49 and bearing 119, and then unscrew threaded outer bearing housing 141 which moves shaft 49 outwardly and upwardly from its position as shown in Fig. 3 to its position as shown in Fig. 5 at which point collar 103 is in engagement with stuffing box end 69 or gasket 113 as shown in Fig. 4. Coupling 57 is sufficiently flexible so that shaft 49 can be moved relative to quill 51 through a sufficient longitudinal distance to actuate the above auxiliary sealing device without requiring the disassembling of said coupling.

Although in the above arrangement of the mixing apparatus it has been shown as a side entering mixer, it is to be realized that the above mixer is adaptable for use as a top entering mixer by merely securing it to a flanged nozzle (not shown) on the top of a receptacle. Moreover, if it is desired, the above mixer can be mounted on a suitable frame (not shown) for use with an open top tank.

Notwithstanding the fact that in the above arrangements of the mixing apparatus the stuffing box has been shown comprising an extension thereof which forms a flushing chamber, it is evident that in many instances it will be unnecessary or undesirable to include such a flushing chamber, and this feature may be dispensed with without affecting the operation of the above auxiliary sealing means. When the mixer is operated in corrosive materials requiring the use of special alloy constructions, as, for example, stainless steel, the omission of the flushing chamber will result in considerable saving in the cost of construction.

The above mixing device can be readily arranged for operation as a bottom entering mixer for a liquid container such as partly shown at 173 (Fig. 6), having a bottom portion 175 formed with a nozzle 177 which has at the outer end thereof a flanged portion 179. In this instance, stuffing box 67, flushing chamber 86 and flange 41 are removed from the inner end of inner flange section 33, as shown in Fig. 3, and are secured by bolts 43 to flange 179 as shown in Figs. 6, 7 and 8. A flat plate 181 (Fig. 6), forming a base for supporting the mixing device, is fastened to the lower end of frame section 33 by suitable bolt means (not shown).

Shaft 49 is replaced by a similar shaft 183 (Figs. 7 and 8) having the same diameter but somewhat longer. Outer bearing housing cap 171 is removed and shaft 183 extends outwardly through said bearing housing, through stuffing box 67 and into container 173 as shown in Fig. 7. Shaft 183 is secured to outer bearing sleeve 157 by snap rings 165 and 167 in the same manner as was shaft 49, and extends through frame 31 to a point below the lower or inner shaft bearing structure as 47 shown in Fig. 7.

In addition, the above mixing device, when arranged as a bottom entering mixer, has an auxiliary sealing means similar to that described above, by means of which the contents of the receptacle may be prevented from escaping into stuffing box 67 when packing 77 is removed. The auxiliary sealing means comprises collar 103 secured by set screw 105 to shaft 183 at a point between stuffing box end 69 and flushing cavity

housing end 89 (Fig. 7). It is evident from an inspection of Fig. 8 that unscrewing bearing housing 141 causes housing, bearing structure 45, and shaft 183 to move upwardly from their normal positions as shown in Fig. 7 to their second positions as shown in Fig. 8. In this instance shaft 183 moves inwardly through stuffing box 67, and the temporary sealing is completed when collar 103 is brought into sealing engagement with either flushing cavity end 89, or gasket 113 which is interposed between said collar and flushing cavity end, as shown in Fig. 8, when the tank contains toxic gases and the like.

Thus, it will be seen that the above invention provides a compact mixing device which is economically and conveniently adapted for use as either a side, top or bottom entering mixer, and which in all cases is provided with an improved temporary auxiliary sealing means to prevent the contents of the receptacle from leaking into the stuffing box while the stuffing box packing is being removed and replaced, even though the level of the contents in the container is above said stuffing box. This auxiliary sealing means is conveniently operated without tools by means of the threaded housing part 141 and handles 143. The above mixing device is also provided with an improved flushing chamber whereby the contents of the receptacle are prevented from contacting the temporary sealing means and stuffing box packing.

It will thus be seen that the invention accomplishes its objects and while it has been herein disclosed by reference to the details of preferred embodiments, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. A mixing device for use with a fluid-containing receptacle having an opening in a wall thereof, said mixing device comprising a rotatable shaft extending through said opening, a stuffing box closing said opening around said shaft, packing means in said stuffing box accessible through the outer end thereof and from the exterior of the receptacle, an auxiliary sealing means on said shaft adapted for sealing engagement with said stuffing box when the shaft is moved longitudinally through said stuffing box, a supporting frame, bearing means on said frame for rotatably supporting said shaft, and means threadedly engaging said frame and connected with one of said bearing means for moving said one of said bearing means and said shaft longitudinally relative to said frame to bring said auxiliary sealing means into sealing contact with said stuffing box for sealing said opening during withdrawal of said packing means from said stuffing box.

2. A mixing device as specified in claim 1 comprising a collar mounted on said shaft in normally spaced relation with the end of said stuffing box and adapted to be engaged therewith to seal the same by outward longitudinal movement of said shaft.

3. A mixing device for use with a fluid-containing receptacle having an opening in a wall thereof, said mixing device comprising a rotatable shaft extending through said opening, a stuffing box closing said opening around said shaft, packing means in said stuffing box ac-

cessible through the outer end thereof and from the exterior of the receptacle, an auxiliary sealing means on said shaft adapted for sealing engagement with said stuffing box when the shaft is moved longitudinally through said stuffing box, a supporting frame, spaced bearing means for said shaft, one of which has a part releasably fixed to said shaft and the other of which is movably mounted on said frame and means threadedly engaging said frame and connected with said other bearing means for moving said other bearing means and shaft longitudinally relative to said frame to bring said auxiliary sealing means into sealing contact with said stuffing box for sealing said opening during withdrawal of said packing means from said stuffing box.

4. A mixing device for use with a fluid-containing receptacle having an opening in a wall thereof, said mixing device comprising a rotatable shaft extending through said opening, a stuffing box closing said opening around said shaft, packing means in said stuffing box accessible through the outer end thereof and from the exterior of the receptacle, an auxiliary sealing means on said shaft adapted for sealing engagement with said stuffing box when the shaft is moved longitudinally through said stuffing box, a supporting frame, spaced bearing means on said frame for supporting said shaft for rotation and longitudinal adjustment, and means threadedly engaging said frame and connected with one of said bearing means for moving said bearing means and shaft longitudinally to bring said auxiliary sealing means into sealing contact with said stuffing box for sealing said opening during withdrawal of said packing means from said stuffing box, the other of said bearing means having a part releasably fixed to said shaft for allowing longitudinal movement of said shaft relative thereto, the first mentioned bearing means having a part releasably fixed to said shaft for releasing the same for withdrawal longitudinally from said frame.

5. A mixing device as specified in claim 4 in which each of said bearing means comprises a split sleeve releasably clamped to said shaft for releasing said shaft for longitudinal movement through said bearing means.

6. A mixing device for use with a fluid-containing receptacle having an opening in a wall thereof, said mixing device comprising a rotatable shaft extending through said opening, a stuffing box closing said opening around said shaft, packing means in said stuffing box accessible through the outer end thereof and from the exterior of the receptacle, an auxiliary sealing means on said shaft adapted for sealing engagement with said stuffing box when the shaft is moved longitudinally through said stuffing box, said stuffing box having at the inner end thereof a housing enclosing said shaft and sealing means and forming a flushing chamber, means for supplying said chamber with a flushing fluid under pressure for preventing the contents of said receptacle from contacting said sealing means and packing means, a supporting frame, bearing means on said frame for rotatably supporting said shaft, and means threadedly engaging said frame and connected with one of said bearing means for moving the same and said shaft longitudinally relative to said frame to bring said sealing means into sealing contact with said stuffing box for sealing said opening during withdrawal of said packing means from said stuffing box.

7. A mixing device for use with a fluid-containing receptacle having an opening in a wall thereof, said mixing device comprising a rotatable shaft extending through said opening, a stuffing box closing said opening around said shaft, packing means in said stuffing box accessible through the outer end thereof and from the exterior of the receptacle, an auxiliary sealing means on said shaft adapted for sealing engagement with said stuffing box when the shaft is moved longitudinally through said stuffing box, said stuffing box having at the inner end thereof a housing enclosing said shaft and sealing means and forming a flushing chamber, means for supplying said chamber with a flushing fluid under pressure for preventing the contents of said receptacle from contacting said sealing means and packing means, gasket means sealing the inner end of said housing to said shaft, a supporting frame, bearing means movably mounted on said frame for rotatably supporting said shaft, and means threadedly engaging said frame and connected with one of said bearing means for moving said one of said bearing means and said shaft longitudinally to bring said auxiliary sealing means into sealing contact with said stuffing box for sealing said opening during withdrawal of said packing means from said stuffing box.

8. A mixing device for use with a fluid-containing receptacle having an opening in a wall thereof, said mixing device comprising a rotatable shaft extending through said opening, a stuffing box closing said opening around said shaft, packing means in said stuffing box accessible through the outer end thereof and from the exterior of the receptacle, an auxiliary sealing means on said shaft adapted for sealing engagement with said stuffing box when the shaft is moved longitudinally through said stuffing box, said stuffing box having at the inner end thereof a housing enclosing said shaft and sealing means and forming a flushing chamber, means for supplying said chamber with a flushing fluid under pressure for preventing the contents of said receptacle from contacting said sealing means and packing means, gasket means sealing the inner end of said housing to said shaft, a supporting frame, spaced bearing means on said frame for supporting said shaft for rotation and for longitudinal adjustment, and means threadedly engaging said frame and connected with one of said bearing means for moving said bearing means and shaft longitudinally to bring said auxiliary sealing means into sealing contact with said stuffing box for sealing said opening during withdrawal of said packing means from said stuffing box, the other of said bearing means having a part releasably fixed to said shaft for allowing longitudinal movement of said shaft relative thereto, the first mentioned bearing means having a part detachably fixed to said shaft for releasing the same for withdrawal longitudinally from said frame.

RICHARD D. BOUTROS.
